UNITED STATES PATENT OFFICE.

WILLIAM BOLLWAHN, OF SHARON, WISCONSIN.

NUT-LOCK.

No. 866,616.

Specification of Letters Patent.

Patented Sept. 24, 1907.

Application filed May 11, 1907. Serial No. 373,074.

To all whom it may concern:

Be it known that I, WILLIAM BOLLWAHN, a citizen of the United States, residing at Sharon, in the county of Walworth and State of Wisconsin, have invented certain new and useful Improvements in Nut-Locks, of which the following is a specification, reference being had therein to the accompanying drawing.

My invention relates to improvements in nut and bolt locks and consists in the novel construction and 10 the combination and arrangement of parts hereinafter described and claimed.

The object of the invention is to provide a simple and practical device of this character which may be readily applied and locked, which will effectively prevent 15 the locked parts from working loose and which when so desired may be readily unlocked.

The above and other objects which will appear as the nature of the invention is better understood are attained in the preferred embodiment of the invention, 20 illustrated in the accompanying drawings, in which

Figure 1 is a sectional view through my improved nut and bolt locking device, showing the use of the same; Fig. 2 is a similar view taken on a plane at right angles; Fig. 3 is a perspective view of one of the locking plates; Fig. 4 is a similar view of the spring washer; Fig. 5 is a perspective of the ratchet washer; and Fig. 6 is a detail view of the ratchet nut.

Referring to the drawings, 1 denotes the part or parts to be united by the bolt 2 and through which the latter passes. Said part or parts 1 may be an object or element of any description. Arranged upon the opposite faces of the part 1 are two locking plates 3, 4 formed with elongated openings 5, 6 adapted to register with the bolt opening in the part 1 and also formed with one 35 or more apertures 7 for the reception of screws, bolts or other fastenings 8 by means of which said plates are secured against rotation. The bolt 2 has a head at one end adjacent to which is formed an enlarged rectangular or flattened portion 9 which is adapted to enter the 40 elongated opening 5 in the plate 3 so that the bolt will be held against rotation by said plate 3. The opposite end of the bolt is screw threaded and projects through the elongated opening 6 in the plate 4 and is adapted to receive a ratchet washer 10 and a ratchet nut 11. The 45 latter is formed upon its inner face with an annular series of radially extending ratchet teeth 12 adapted to engage a similar series of ratchet teeth 13 upon the outer face of the washer 10. The inner face of this washer is formed with inwardly extending lugs or projections 14 50 which are adapted to enter the opening 6 in the plate 4 so that the washer will be locked against rotation by said plate. A spring washer 15 preferably in the form of a piece of resilient metal bent into substantially cir-

cular form and having its ends sprung outwardly in opposite directions to form biting teeth or spurs, is arranged upon the bolt 2 between its head and the outer face of the bolt locking plate 3.

In applying the improved bolt and nut lock to the object or element upon which it is to be used, the plates 3, 4 are first secured upon the opposite faces of the same 60 with their elongated openings in alinement with the bolt opening and the bolt is then passed through said plates and the object or element 1, the spring washer 15 having been first slipped upon the bolt. The ratchet washer is then placed upon the projecting threaded end 65 of the bolt and its lugs 14 projected into the ends of the opening 6 in the plate 4. The ratchet nut is then screwed up upon the bolt against the ratchet washer until the parts are drawn together. As the nut is tightened the spring washer 15 permits the ratchet teeth 12, 70 13 upon the nut and washer to slip over each other but said teeth will effectively prevent the reverse rotation of the nut. In applying the device, I preferably employ the gripping tool set forth in an application filed by me May 11, 1907 and bearing Serial Number 373,073. 75

It will be seen that when the nut has been applied and tightened it will be impossible for it to work loose and that the only way in which it can be removed is by loosening the screws or fastenings 8 in the plate 3 and rotating said plate so as to screw the bolt out of the nut. 80 The engagement of the rectangular or polygonal shaped portion 9 of the bolt with the elongated opening 5 in the plate 3 causes the bolt to be locked for rotation with said plate.

Having thus described my invention, what I claim 85 and desire to secure by Letters Patent is:—

The combination with an apertured object or element, locking plates arranged upon opposite faces of said object and having elongated openings to align with the aperture in said object, a bolt passed through said plates and said object and having at one end a head and an adjacent enlarged portion to enter the elongated opening in one of said plates whereby said bolt and plate will be locked together, a spring washer arranged upon the enlarged portion of the bolt between the bolt head and the adjacent locking plate, a ratchet washer arranged upon the threaded end of the bolt and having projections to enter the elongated opening in the adjacent locking plate, a ratchet nut screwed upon the threaded end of said bolt and against said ratchet washer, and fastenings uniting said locking 100 plates to said object, the fastenings uniting the locking plate adjacent to the head of the bolt being removable whereby said plate may be rotated to screw the bolt out of the nut, substantially as and for the purpose set forth.

In testimony whereof I hereunto affix my signature in 105 presence of two witnesses.

WILLIAM BOLLWAHN.
